UNITED STATES PATENT OFFICE.

FRANK E. DE LONG, OF PHILADELPHIA, PENNSYLVANIA.

DESIGN FOR A PAPER-FASTENER.

SPECIFICATION forming part of Design No. 34,560, dated May 28, 1901.

Application filed April 12, 1901. Serial No. 55,551. Term of patent 14 years.

To all whom it may concern:

Be it known that I, FRANK E. DE LONG, a citizen of the United States, residing in the city of Philadelphia, in the county of Philadelphia and State of Pennsylvania, have invented and produced a new and useful Design for a Paper-Fastener, of which the following is a specification, reference being had to the accompanying drawing, forming part thereof.

The drawing is a view in front elevation of a paper fastener showing my design.

The leading feature of my design consists of a pair of approximately straight crossed arms, a transversely disposed base piece continuous and connective of said arms, and eyes formed at the outer ends of said arms.

The eyes occupy such relation to the arms

that the latter extend transversely across, that is to say, directly in front of, the respective ends of the wire of which said eyes are formed.

The base piece is designated *c*, the arms *a*, *b*, and the eyes *d*.

Having thus described my invention, I claim and desire to secure by Letters Patent—

The design for a paper fastener, as herein shown and described.

In testimony that I claim the foregoing as my invention I have hereunto signed my name this 6th day of March, A. D. 1901.

FRANK E. DE LONG.

In presence of—

S. SALOME BROOKE,
F. NORMAN DIXON.
